J. BARKER

FOUNTAIN PEN

Filed Sept. 10, 1925

UNITED STATES PATENT OFFICE.

JAMES BARKER, OF KALAMAZOO, MICHIGAN.

FOUNTAIN PEN.

Application filed September 10, 1925. Serial No. 55,551.

To all whom it may concern:

Be it known that I, JAMES BARKER, a citizen of the United States, residing at the city and county of Kalamazoo, State of Michigan, have invented certain new and useful Improvements in Fountain Pens, of which the following is a specification.

This invention relates to improvements in fountain pens.

10 The main objects of this invention are to provide an improved fountain pen in which the cap is securely retained upon the barrel and at the same time may be readily removed as occasion requires.

15 Objects relating to details and economies of construction and operation of my invention will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing, forming a part of this application, in which:

Fig. 1 is a side view of my improved fountain pen.

Fig. 2 is a detail view with the cap in section on a line corresponding to line 2—2 of Fig. 1.

Fig. 3 is a transverse section on a line corresponding to line 3—3 of Fig. 2.

Fig. 4 is a detail view partially in section with the cap arranged upon the outer end of the barrel.

Fig. 5 is a perspective view of the locking detent and its supporting spring.

Fig. 6 is a detail view partially in section of a modified form or embodiment of my invention.

Fig. 7 is a transverse section corresponding to that of Fig. 3 showing another modification or embodiment of my invention.

45 In the drawing similar reference characters refer to similar parts throughout the several views, and the sectional views are taken looking in the direction of the little arrows at the ends of the section lines.

50 Referring to the drawing, 1 represents the barrel of my improved fountain pen which is provided with an annular groove 2 in spaced relation to the inner end thereof and an annular groove 3 in spaced relation to its outer end.

The cap 4, in the embodiment illustrated,

is internally threaded at 5 to engage threads 6. These threads, however, may be dispensed with, with satisfactory results. The cap has an annular groove 7 therein 60 and a hole 8 aligned with the groove in the barrel when the cap is arranged on either end of the barrel.

A detent carrying spring 9 in the form of a split ring with overlapping ends is arranged in this groove 7 of the cap, the inner end of the spring having a hole 10 therein through which a detent 11 secured to the outer end of the spring is disposed, this detent projecting through a sole 8 in the cap 70 to engage the groove in the barrel thereby effectively securing the cap in position. The detent has a head 12 at its inner end so that it cannot be pulled through the hole 10 in the inner end of the spring, the head 75 serving as a retaining means for the spring.

The end 13 of the spring serves as a finger piece to facilitate in disengaging the detent from the groove permitting the removal of the cap. 80

In the modification shown in Fig. 6, the cap 14 is provided with a combined pocket clip and detent carrying spring 15 disposed longitudinally of the cap, the detent 16 being secured on the inner end of this spring 85 to project through a hole 17 in the cap into engagement with the grooves in the barrel.

In the modification shown in Fig. 7, the retaining ring 18 embraces the cap and has outwardly projecting ears 19 thereon in 90 which the lever-like detent carrying member 20 is pivoted, the detent 21 projecting through a hole in the cap to engage the groove, the outer end of this lever 20 being engaged by the end 22 of the band 18 which 95 constitutes a spring for holding the detent in engagement.

I have not attempted to illustrate or describe other embodiments or adaptations of my invention as I believe the disclosure 100 made will enable those skilled in the art to embody or adapt my improvements as may be desired.

Having thus described my invention, what I claim as new and desire to secure by 105 Letters Patent, is:

1. In a fountain pen, the combination with the barrel provided with an annular groove spaced from the end thereof, of a cap adapted to telescope with said barrel, said cap having an annular groove and a hole 110 therethrough registering with said grooves

- when the cap is engaged upon the barrel, an annular spring having overlapping ends arranged in said groove in said cap, and a headed detent secured to the outer end 5 of said spring and arranged through an opening in the inner end thereof to project through said hole in said cap into said barrel groove for detachably securing the cap upon the barrel.
- 10 2. In a fountain pen, the combination with the barrel provided with an annular groove spaced from the end thereof, of a cap adapted to telescope with said barrel, said cap having a hole therethrough registering with said grooves when the cap is engaged upon the barrel, an annular spring having overlapping ends embracing said cap, and a headed detent secured to the outer end of said spring and arranged 15 through an opening in the inner end thereof to project through said hole in said cap to engage said groove for detachably securing the cap upon the barrel.
- 15 3. In a fountain pen, the combination with the barrel provided with an annular groove spaced from the end thereof, of a cap adapted to telescope with said barrel, said cap having a hole therethrough registering with said grooves when the cap is engaged upon the barrel, an annular spring embracing said cap, and a detent secured to 20 one end of said spring and arranged to project through said hole in said cap to engage said groove for detachably securing the cap upon the barrel.
- 20 4. In a fountain pen, the combination with the barrel having an annular groove adjacent the end thereof, of a cap adapted to telescope with said barrel and having a hole therein aligned with said groove when the cap is in position, and a detent carrying spring secured to said cap and provided with a detent arranged through said hole therein to detachably engage said groove.
- 25 5. In a fountain pen, the combination of the barrel having an annular groove adjacent one end thereof, a cap adapted to telescope with said barrel and having an opening therein registering with said groove when the cap is in position, and a spring 30 pressed detent arranged through said opening in said cap to engage said groove.
- 30 6. In a fountain pen, the combination with the barrel having a recess adjacent one end thereof, of a cap adapted to telescope with said barrel and having an opening therein registering with said recess when the cap is in position, and a detent mounted in said cap to project through said opening 35 therein to engage said recess.

In witness whereof I have hereunto set my hand.

JAMES BARKER.
